UNITED STATES PATENT OFFICE.

FRANK VAN HENNIK, OF YONKERS, NEW YORK.

GAME.

SPECIFICATION forming part of Letters Patent No. 623,344, dated April 18, 1899.

Application filed June 2, 1898. Serial No. 682,341. (No model.)

To all whom it may concern:

Be it known that I, FRANK VAN HENNIK, a citizen of the United States of America, and a resident of Yonkers, county of Westchester, 5 and State of New York, have invented certain new and useful Improvements in Games, of which the following is a specification.

This invention comprises a horizontal game-board with movable elements. Upon this 10 game-board men are moved as indicated by the dice throws of the respective players on a "field of play" which is ruled in a series of parallel courses, these being subdivided into oblong spaces or stations. Certain of the stations on this board are given designations 15 which are used in the game of basket-ball. The game-board is also provided with alleys along which marbles are aimed for depressions known as baskets.

20 In the accompanying drawing, which forms a part of this specification, the figure shows a game-board embodying my invention, together with the accessory elements for playing the game.

25 The game-board, which is surrounded by a frame, is divided into three sections—a field of play *f* and two alleys *a a*. These three sections are separated from each other by the two partitions *p p*. The field of play is in 30 the middle. It is subdivided by four lines into five longitudinal courses. These courses are designated at both ends by numbers from "1" to "5," by which the courses are known to the players of the game. The numbers at 35 one end designate the courses and the men placed on them to the player or players on the one side, while the numbers at the opposite end are for the player or players of the other side. The numbers at each end if 40 viewed from the end at which they are placed read from right to left in the order 5 3 1 2 4. The numbers at the opposite ends of any course are therefore not the same, with the exception of the center course. Parallel 45 cross-lines subdivide the five courses into oblong spaces or stations. Certain of these stations, which hold corresponding positions on all the courses, are designated by the terms "Shoot," "Out of bounds," and "Foul," the 50 terms being taken from the game of basket-ball. Stations bearing these names have different colors, but all stations of the same name

are marked by the same color. The differently-colored stations are represented in the drawing by distinctive forms of shading. Each 55 end of the field of play is marked "Home."

The alleys *a a* are narrow courses separated from the field of play by partitions and extending lengthwise of the game-board. Near one end of each alley is a spot *s*. Near the 60 other end of each alley is a depression *d*, called a "basket." The spot of one alley is at one end of the board and the spot of the other alley is at the opposite end of the board. On the side frame at each end of the game-board 65 is a row of holes, in which a pin may be moved along to keep the score.

The game is played with two teams of five men each. The men *m* of one team are shaded dark to distinguish them from the men *n* on 70 the opposing team, which are shaded light. In each team the man starting on station No. 1 is known as "center," on No. 2 as "right forward," on No. 3 as "left forward," on No. 4 as "right guard," and on No. 5 as "left 75 guard." Each side is provided with a small ball *r*, which is used only in the alleys. Each side is also provided with a dice-box and dice. In the figure these are shown for convenience 80 in the alleys. When the ball is in play, they are, however, removed. The spot *s* in each alley is the starting-point for the ball, and the basket is the goal. The ball is propelled by a snap of the finger.

The game may be played by two or more 85 persons. If played by more than two, the players will divide between the two sides and the players on each side will take turns. At the opening of the game the teams of men are set out at the ends of the courses on the stations which are marked "Home." One side then commences the play by a dice throw. If "6" is thrown, the play is lost. Otherwise the player is allowed to move out one space that man whose number corresponds to the 90 dice throw. The play then passes alternately between the sides. On any succeeding throw the player is entitled to move forward as many stations as the dice throw any man that has already been moved from the end station of 95 the course, or if the number thrown corresponds to the number of a man still on the home-line that man may be moved forward one station. If a move places a man on a space

marked "Shoot," the player is entitled to a shoot for the basket, which, if made, counts two points. Should a player by moving put a man on a station on his side of the center 5 of the board which is marked "Out of bounds," he is required to move the man back three stations to a station marked "Shoot" and give the opposing side a shoot for the basket, which, if made, will give that side two points. Should 10 a player by moving put a man on a station beyond the center of the board which is marked "Out of bounds," he is required to move the man back three stations to a station marked "Foul," and the opposing side is given a shoot 15 for the basket, which, if made, will give that side one point. Should a player by moving forward put a man on a station marked "Foul," he must return the man to the beginning of the course, and the man can be 20 again started only on its number being thrown, as in the beginning of the game. This also gives the opposing side a shoot for the basket, which, if made, gives that side one point. Should a player by moving put a man on the 25 station marked "Home" at the farther end of the course, he is given a shoot for the basket, which, if made, counts two points. No

man can be moved onto the space occupied by another man; but one man can jump another man. If no man can be moved the number of stations indicated by the throw except by moving onto a space already occupied, the 30 turn is lost.

Having described my invention, what I claim, and desire to secure by Letters Patent 35 of the United States, is—

In a game-board, a field of play ruled in courses which are subdivided into stations, certain of which are designated by terms which are used in the game of basket-ball, in 40 combination with alleys ranged along the sides of the field of play, each alley having a depression *d*, forming a basket at its one end, and a spot *r* at its opposite end, the spots and baskets being located at diagonally opposite 45 corners of the board, substantially as described.

Signed by me, in Yonkers, New York, this 24th day of May, 1898.

FRANK VAN HENNIK.
